(57) **CLAIM**

The ornamental design for a device for filling multiple water balloons, as shown and described.

DESCRIPTION

FIG. 1 is a top perspective view of a device for filling multiple water balloons in accordance with the present design;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

In the drawings, the claimed design is defined by the shaded surfaces; broken lines immediately adjacent shaded surfaces represent boundaries of the claim and form no part thereof; all other broken lines depict unclaimed environmental subject matter and form no part of the claim.

1 Claim, 6 Drawing Sheets
